WINDOW REGULATOR

Harold W. Pierce, Farmington, Mich., assignor to Ford Motor Company, Dearborn, Mich., a corporation of Delaware

Application September 4, 1957, Serial No. 682,019

10 Claims. (Cl. 268—126)

This invention relates generally to window regulators for motor vehicles, and has particular reference to window regulator mechanism adapted to control the movement of a vehicle window in a predetermined combined horizontal and vertical path.

An object of the invention is to provide a window regulator for a motor vehicle which is arranged to initially move the window a short distance in a general horizontal direction, and to subsequently move the window in a general downward direction.

Other objects and advantages of this invention will be made more apparent as this description proceeds, particularly when considered in connection with the accompanying drawings, wherein:

The single figure is a side elevational view of a window and window regulator mechanism incorporating the present invention.

Referring now to the drawings, the reference character 11 indicates a motor vehicle window having a frame 12. The lower rail 13 of the window frame 12 is formed with an elongated generally horizontal slot 14 and with a depending flange 16 adjacent its forward portion.

A toothed regulator quadrant 17 is pivotally mounted at 18 upon the vehicle body, and is conventionally actuated by means of a pinion (not shown) which may be either manually or power driven.

A pair of regulator cross arms are provided. The front arm 19 is pivotally connected at 21 to the regulator quadrant 17 at a point spaced from the pivotal mounting 18 of the quadrant. The opposite end of the regulator arm 19 carries a roller 22 slidably received within the slot 14 in the window frame rail 13.

The second regulator arm 23 is pivotally mounted at 24 upon the vehicle body, and at its opposite end supports a roller 26 slidably received within the slot 14 in the window frame rail 13.

It will be noted that the regulator arms 19 and 23 cross each other, not only in the raised position of the window, but also in all positions during the raising and lowering of the window. The movement of the two regulator arms is coordinated by means of a curved guide slot 27 formed in the regulator arm 23 and slidably receiving a pin 28 carried by the regulator arm 19. The pin 28 may be equipped with anti-friction or rollable means if desired.

A curved generally vertically extending guideway 29 is mounted upon the vehicle body beneath the forward portion of the closed position of the window. A roller 31 carried by the depending flange 16 of the window frame rail 13 slidably engages the guideway 29.

In the present instance, the front guideway 29 has an upper portion inclined rearwardly and downwardly and a lower portion inclined more sharply downwardly. The guide slot 27 in the regulator arm 23 is likewise formed in a compound curve and the two guideways, together with the geometrical arrangement of the pivotal connections of the regulator cross arms, are arranged in such fashion as to control the path of movement of the window 11 so that it will clear existing body obstructions

2

and may be stored within the vehicle body in the space available. With this arrangement, the lower front corner 32 of the window 11 follows a path 32' as the window is lowered, and it will be noted that the corner moves first rearwardly and then downwardly to clear the body pillar 33. The paths of movement of the points 21, 28, 22 and 26 are plotted on the drawing as lines 21', 28', 22' and 26' respectively.

From the foregoing, it will be seen that the interaction 10 between the regulator cross arms determined by the configuration by the guide slot 27 results in a predetermined variable relationship between the regulator arms to properly control the window position during its raising and lowering movements. Different window paths 15 can be obtained by suitable variations in the shape of the guide slot 27. Fore and aft window positions may also be varied by suitable changes in the curvature of the front guideway 29. If desired, this guideway can be mounted adjacent the rear edge of the window instead 20 of near the front as shown.

It will be understood that the invention is not to be limited to the exact construction shown and described, but that various changes and modifications may be made without departing from the spirit and scope of the invention, as defined in the appended claims.

What is claimed is:

1. In a window control mechanism for raising and lowering a window in a motor vehicle body, a first regulator arm pivotally connected at one end to said vehicle body for swinging movement about a fixed pivot axis and at its opposite end to said window, a regulator member pivotally mounted upon said vehicle body, a second regulator arm pivotally connected at one end to said regulator member for bodily shiftable movement therewith and swinging movement relative thereto and at its opposite end to said window at a point spaced from the point of connection of said first regulator arm to said window, interacting cam means on intermediate portions of said regulator arms to control the relative movement 30 between said regulator arms, and means actuating said regulator member to effect a raising or lowering of said window.

2. In a window control mechanism for raising and lowering a window in a motor vehicle body, a first regulator arm pivotally connected at one end to said vehicle body for swinging movement about a fixed pivot axis and at its opposite end to said window, a regulator member pivotally mounted upon said vehicle body, a second regulator arm pivotally connected at one end to said regulator member for bodily shiftable movement therewith and swinging movement relative thereto and at its opposite end to said window at a point spaced from the point of connection of said first regulator arm to said window, said regulator arms crossing each other in all positions of said window, a curved guideway on 45 one of said regulator arms, means on the other of said regulator arms slidably engaging said guideway and forming a movable pivotal connection between said regulator arms, and means actuating said regulator member to effect a raising or lowering of said window.

3. In a window control mechanism for raising and lowering a window in a motor vehicle body, a pair of crossed regulator arms having slidable connections with the lower portion of said window, one of said crossed regulator arms having a slot in its intermediate portion, 50 a follower on the other of said regulator arms slidably within said slot, a curved generally vertically extending guideway mounted on said vehicle body, means on said window engaging said guideway, said last mentioned means in cooperation with said guideway being effective to control movement of the window laterally of the direction of raising and lowering movements thereof, and

65 4. In a window control mechanism for raising and lowering a window in a motor vehicle body, a pair of crossed regulator arms having slidable connections with the lower portion of said window, one of said crossed regulator arms having a slot in its intermediate portion, a follower on the other of said regulator arms slidably within said slot, a curved generally vertically extending guideway mounted on said vehicle body, means on said window engaging said guideway, said last mentioned means in cooperation with said guideway being effective to control movement of the window laterally of the direction of raising and lowering movements thereof, and

actuating means for raising and lowering said window.

4. In a window control mechanism for raising and lowering a window in a motor vehicle body, a pair of crossed regulator arms having slidable connections with the lower portion of said window, said regulator arms being supported upon said vehicle body beneath the central portion of the closed position of said window, one of said crossed regulator arms having a curved slot formed therein, means carried by the other of said regulator arms slidable within said slot and forming the sole connection between said arms, a curved generally vertically extending guideway mounted on said vehicle body, adjacent one end of the closed position of said window, means on said window slidably engaging said guideway, said last mentioned means in cooperation with said guideway being effective to control movement of the window laterally of the direction of raising and lowering movements thereof, and regulator mechanism operatively connected to one of said regulator arms to raise and lower said window in a predetermined path.

5. In a window control mechanism for raising and lowering a window in a motor vehicle body, a pair of regulator arms supported upon said vehicle body for swinging movements and having connections to said window at spaced points, actuating means pivotally mounted on said vehicle body, means pivotally connecting said actuating means to one of said regulator arms for imparting swinging movement thereto, and cam means on an intermediate part of one of said regulator arms engageable with an intermediate part of the other of said regulator arms, said cam means being effective to control the movements of said regulator arms in a predetermined relationship to raise and lower said window.

6. In a window control mechanism for raising and lowering a window in a motor vehicle body, a pair of regulator arms supported upon said vehicle body for swinging movements and having connections to said window at spaced points, actuating means pivotally mounted on said vehicle body, means pivotally connecting said actuating means to one of said regulator arms for imparting swinging movement thereto, a curved guideway on one of said regulator arms, and means on the other of said regulator arms slidably engaging said guideway and forming the sole connection between said arms.

7. In a window control mechanism for raising and lowering a window in a motor vehicle body, a generally vertically extending guideway mounted upon said vehicle body, means on said window slidably engaging said guideway, a pair of regulator arms supported upon said vehicle body for pivotal movement and having sliding connections with the lower portion of said window at spaced points, regulator mechanism for actuating one of said regulator arms to raise and lower said window, means pivotally connecting said regulator mechanism to said one regulator arm, a curved guideway on one of said regulator arms, and a follower on the other of said regulator arms slidably engaging said curved guideway and movable therealong to control the relationship between said regulator arms as said window is raised and lowered.

8. In a window control mechanism for raising and lowering a window into and out of a storage space in a vehicle body, a first window regulator arm pivotally connected at one end thereof to said vehicle body for swinging movement about a fixed axis located intermediate the ends of said storage space, means pivotally connecting the other end of said first regulator arm to said window adjacent one end of the latter, a regulator member pivotally mounted upon said vehicle body intermediate the ends of said storage space, a second regulator arm pivotally connected at one end to said regulator member for swinging movement relative to the latter and for bodily shiftable movement thereby, coacting

cam means on intermediate portions of said regulator arms, and means actuating said regulator member to cause bodily shiftable movement of said second regulator arm to effect raising or lowering of said window, said coacting cam means being effective to transmit movement of said second arm to said first arm to maintain said window in a predetermined condition of stability.

9. In a window control mechanism for raising and lowering a window into and out of a storage space in a vehicle body, a first window regulator arm pivotally connected at one end thereof to said vehicle body for swinging movement about a fixed axis located intermediate the ends of said storage space, means pivotally connecting the other end of said first regulator arm to said window adjacent one end of the latter, a regulator member pivotally mounted upon said vehicle body intermediate the ends of said storage space, a second regulator arm pivotally connected at one end to said regulator member for swinging movement relative to the latter and for bodily shiftable movement thereby, the pivot axis of said second regulator arm being spaced from the pivot axis of said regulator member, coacting cam means on intermediate portions of said regulator arms, means actuating said regulator member to cause bodily shiftable movement of said second regulator arm to effect raising or lowering of said window, said coacting cam means being effective to transmit movement of said second arm to said first arm to maintain said window in a predetermined condition of stability, and coacting means on said vehicle body and window adjacent the other end of the latter effective to control movement of the window laterally of the direction of raising and lowering movements thereof.

10. In a window control mechanism for raising and lowering a window into and out of a storage space in a vehicle body, a first window regulator arm pivotally connected at one end thereof to said vehicle body for swinging movement about a fixed axis located intermediate the ends of said storage space, means pivotally connecting the other end of said first regulator arm to said window adjacent one end of the latter, a regulator member pivotally mounted upon said vehicle body intermediate the ends of said storage space, a second regulator arm pivotally connected at one end to said regulator member for swinging movement relative to the latter and for bodily shiftable movement thereby, the pivot axis of said second regulator arm being spaced from the pivot axis of said regulator member, coacting cam means on intermediate portions of said regulator arms, means actuating said regulator member to cause bodily shiftable movement of said second regulator arm to effect raising or lowering of said window, said coacting cam means being effective to transmit movement of said second arm to said first arm to maintain said window in a predetermined condition of stability, and coacting means on said vehicle body and window adjacent the other end of the latter effective to control movement of the window laterally of the direction of raising and lowering movements thereof.
